STRINGED MUSICAL INSTRUMENT

Dominick A. Maffei, Bayside, and Clyde C. Doerr,
Forest Hills, N. Y., assignors to Epiphone, Inc.,
New York, N. Y., a corporation of New York

Application September 22, 1939, Serial No. 296,048

11 Claims. (Cl. 84—312)

The present invention relates to stringed musical instruments, especially to instruments of the type of the electric steel guitar, and more particularly to improvements in tuning mechanism for such instruments.

This application for Letters Patent is a continuation-in-part of our copending application Serial Number 265,130, filed March 31, 1939, and relates to certain structural modifications in the improvements therein disclosed.

The principal object of the invention, is to provide tuning means of a novel type which makes it possible to obtain a wide range of pitch variation for each string and to multiply to an extent heretofore unknown the number of chord combinations which may be secured by the player of a stringed musical instrument, whether it be a guitar of the modern electronic type, or any other of the many stringed musical instruments whose musical range has been heretofore limited.

Another object of the present invention is to provide in a stringed musical instrument of the above mentioned type, means by which the player may be enabled to accomplish the frequent and rapid changes in tuning required for the rendition of a musical program under modern conditions.

In furtherance of the aforesaid objects, the invention aims to provide tuning means, auxiliary to the more conventional tuning keys, whereby the tension of each string may be varied selectively at will, with little effort on the part of the player and under his control at all times.

As a feature of the invention, such auxiliary tuning means comprises a series of rotatable rollers mounted on a shaft upon the body of the instrument, each roller being adapted for tensioning one of the strings, the rollers being individually connected to suitable operating levers mounted in a compact group conveniently accessible to the hand of the player.

As a further feature of the invention, this group of operating levers is provided with retaining means whereby each of said levers may be held securely in each of a series of adjusted positions to which it may be moved by a simple, easily made, and rapidly completed adjustive movement.

A particular feature of the invention is the provision of balancing means whereby each of the said rollers is urged into a position of normal tension of the connected string, upon return of its corresponding operating lever to its neutral position.

55 A further feature of the invention is the pro-

vision of means whereby all of the said operating levers may be returned to a neutral position simultaneously by the actuation of a single control device; also the further provision of means whereby the said device for effecting the return of the operating levers to their neutral position, is itself automatically set in an inoperative position leaving the operating levers ready for such further adjustive manipulation as may be desired at any time.

10 Other objects and advantages of the present invention will in part be pointed out hereinafter and will in part be apparent to those skilled in the art to which the present invention relates.

15 With the above and other objects in view the present invention consists of the novel features of construction, combination of elements, and arrangement of parts hereinafter described and illustrated in the accompanying drawings which show the preferred physical embodiment of the 20 invention.

In the accompanying drawings which form an integral part of this specification,

Fig. 1 is a plan view of a stringed musical instrument in the construction of which the present invention has been embodied;

Fig. 2 is a side elevational view thereof;

Fig. 3 is an enlarged view in vertical transverse section, taken on the irregular section line 3—3 of Fig. 1;

Fig. 4 is an enlarged fragmentary detail plan showing the operating levers and cooperating members associated therewith;

Fig. 5 is an enlarged detail view in perspective showing one of the operating levers in operative connection with its corresponding tensioning roller, together with their respectively associated cross-bar, string and balancing spring;

Fig. 6 is an enlarged fragmentary bottom plan view taken on the line 6—6 of Fig. 2, looking upward.

Referring now to the drawings, which illustrate a stringed musical instrument of the electric guitar type in the construction of which the present invention has been embodied, and where like reference characters indicate corresponding parts throughout the several views, B designates generally the body of the instrument comprising a hollow wooden panel 10 of relatively thick hard wood, which is provided on the upper side thereof with a metal plate 11 attached to the panel, as by the studs 12. The body is provided on its upper surface with a suitable fretted fingerboard 13 extending longitudinally thereof in the conventional manner, and with the con-

ventional tuning keys 14 situated at the head portion of the body.

Strings 15 are tensioned over the body of the instrument and extend longitudinally over the fingerboard 13 in the conventional manner. The strings 15 are connected at their outer ends to the conventional tuning keys 14, are guided over suitable guide rolls 16 mounted on a shaft 17 supported by a pair of brackets 18 at the outer end 10 of the fingerboard, and are secured at their inner ends to rotatable rollers 19 mounted on a shaft 20 supported by a pair of brackets 21 at the tailward portion of the body. The rotatable rollers 19 constitute an integral part of the auxiliary tuning mechanism to which the present invention relates and will be referred to more particularly hereinafter.

The instrument selected for illustration being an electric steel guitar, there is shown in Fig. 20 1 an aperture 22 which is provided in the upper side of the body adjacent the tail end of the instrument, beneath which there is mounted a suitable pick-up device 23 of well known type, which is adapted to transmit the sound vibrations of the 25 strings to an amplifier and loud-speaker unit associated with the instrument. The pick-up device 23 is preferably provided with suitable volume and tone control means (not shown) which is inserted in the pick-up circuit for modifying 30 the volume and tone of the string vibrations. These controls are adapted to be manually operated by means of control knobs 24 and 25 which are readily accessible to the hand of the player.

35) In pursuance of the present invention, tuning or string tensioning means of an auxiliary character are provided which are adapted to vary at will the pitch of any of the strings independently of the keys 14 or any other tuning or string tensioning mechanism with which such an instrument may be equipped. A group of such auxiliary tensioning devices is illustrated in the drawings.

This group of auxiliary tensioning devices 45 comprises the rotatable rollers 19, mentioned above, all of which are mounted on a common shaft 20 supported at its ends by the pair of brackets 21. The rollers 19 are spaced apart by spacing members 26 and the lower portions of the rollers are 50 adapted to project below the surface of the instrument through an opening 27 formed in the upper side of the body. Each of the rollers 19 is provided with a crank-arm 28, which depends into the hollow of the body, the end of which is provided with a series of holes 29 adapted to be entered selectively by a pin 30, which couples therewith in adjusted position the end of a link 31. The link 31 extends to a bell crank lever 32 which is pivotally mounted as at 33 on a supporting bar 60 34 secured to the body of the instrument, and is coupled in adjusted position with one arm of the bell crank lever 32 in like manner as aforementioned, by a pin 35 which enters into one of the holes 36. Another link 37 extends from the other 65 arm of the bell crank lever 32 to an operating lever 38, constituting one of a group of such operating levers, and is coupled at both ends in adjusted position, by a pin 39 which enters into one of the holes 40 in the other arm of the bell crank lever 32, and by a pin 41 which enters into one of the holes 42 of the operating lever 38.

The operating levers 38 are preferably in the form of sector plates mounted upright to rotate upon a horizontal shaft 43, common to all the 70 operating levers, the shaft 43 being carried by

suitable supports within the body of the instrument. The operating levers 38 are separated from each other at their pivot points by spacing sleeves 44 and each lever is adapted for manual operation independently of the others. The operating levers 38 extend upwardly through an aperture 45 formed in the upper side of the body of the instrument and their upwardly presented arcuate parts are each provided with a terminal handle or button 46 by which the lever may be 10 selected readily and operated easily by one hand of the player. The group of operating levers 38 is mounted in convenient disposition, as shown in Fig. 1, with that portion of the strings 15 operated upon by the player, and also proximate to 15 the tone and volume control knobs 24 and 25. Preferably the region for manual engagement of the operating levers will be restricted to the area defined by the edges of a frame 47 which is secured to the faceplate 11, over the aperture 45 in 20 which the group of levers 38 is mounted.

In further pursuance of the present invention, and to serve the purpose of retaining means for holding the operating levers 38 in any selected position of several such possible positions, there is 25 provided, in the instance illustrated, a series of index bars 48, one for each lever, each of said index bars 48 being arranged in parallelism with the face of one of the levers and in spaced relation thereto, and secured at the ends thereof to 30 the upper surface of the body of the instrument as by the studs 49. The index bars 48 are preferably arcuate in form to conform to the curvature of the upper portions of the operating levers 38, and the inner edge of each index bar 48 is 35 provided with a plurality of notches or recesses 50 to receive its corresponding lever 38 in say five positions of tensional adjustment of one of the strings. This structure is illustrated in detail in Fig. 4, which figure also shows means for aiding 40 the operating levers 38 to be engaged retentively in their several adjustive positions, while making it possible also to move them freely to different positions of adjustment at will.

For this purpose, the upper portion of the face 45 of each operating lever 38 which is adjacent the recesses 50 of its associated index bar 48, is provided with a resilient finger or prong 51 having a laterally extending bolt 52 which normally bears against the edge of the index bar 50 48 and is adapted to be retentively engaged within any one of the recesses 50. The recesses 50 are preferably tapered inwardly and the bolts 52 are correspondingly tapered to permit of ready locking engagement between the two parts 55 when the operating levers 38 are moved by the player to required adjustive positions, and also to permit the bolts 52 to be easily and readily released from their recesses 50 when the operating levers are moved by the player to other 60 and different adjustive positions.

It will be understood from the foregoing description that the operative connection between each operating lever 38 and its corresponding string tensioning roller 19 is such that upon 65 operation of the lever 38, its pivotal movement will be transmitted by means of the connecting links 37 and 31 and the intermediate bell crank lever 32 to the crank arm 28 of the string tensioning roller 19, and the roller 19 will be caused 70 to rotate in a corresponding manner, whereby the tension of the connected string 15 will be correspondingly varied. The levers 38 and their corresponding tensioning rollers 19 are preferably connected in such operative relation, that 75

when the levers 38 have their handles 46 disposed in a central position with reference to opposite sides of the aperture 45, then the tensioning rollers 19 are in position of normal tension of the connected strings. Accordingly, movement of the levers 38 to one side of their central or neutral positions will cause an increase in the tension of the strings 15 and movement to the opposite side will cause the tension of the strings 15 to be decreased.

In further pursuance of the present invention, each lever 38 is provided with a body opening 53, having downwardly rounded walls forming a groove 54 adjacent to the fulcrum shaft 43, and adapted to receive therein a cross-bar 55 carried by the arms of a pivoted U-shaped lever 56. The U-shaped lever 56 is adapted to embrace all of the levers 38 as a group, its ends being pivoted within the body of the instrument as at 57. The portion 58, which spans the arms of the U-shaped lever 56, projects upwardly through the aperture 45 in the upper side of the body of the instrument, and provides a hand rest for manual operation of the lever.

The cross-bar 55 carried by the U-shaped lever 56 transfixes all the operating levers 38, extending through their body apertures 53 from side to side of the group, and is designed to enter the grooves 54 of the operating levers when the player presses down with his hand on the hand rest 58 of the U-shaped lever 56, to permit the operating levers 38 to be thrown simultaneously into neutral position, so that all of the string tensioning rollers 19 may, at will, be restored to a position of normal tension of the connected strings. Thus, a single volitional act by the player suffices to release the operating levers as a group, from the last adjusted positions to which they may have been moved by the player, and to restore them to their neutral positions.

The underside of the hand rest 58 is preferably provided with soft rubber pads or cushions 59 to ease and absorb the shock that may be produced from the operation of the lever 56.

A spring 60 is provided, and is adapted to engage one of the arms of the U-shaped lever 56 and hold it in inoperative position, wherein the cross-bar 55 is out of engagement position with the grooves 54 of the operating levers 38, as shown in Figs. 3 and 5, so as to permit movement of the operating levers relative to the cross-bar 55 to the desired adjusted positions. When the pressure of the player's hand is removed from the hand rest 58, after the lever 56 has been operated to restore the operating levers 38 to their neutral positions, the spring 60 acts to return the lever 56 to its original inoperative position, and the operating levers are thus free and ready to be again operated as desired.

In further pursuance of the present invention, the tailward portion of each string 15 is attached to its corresponding tensioning roller 19 by coiling it over the roller in the manner indicated in Fig. 5, the end of the string being secured to the roller by a pin (not shown) which is adapted to be engaged within a suitable hole in the periphery of the roller. The tensioning rollers 19 are preferably provided with annular grooves 61 within which the strings 15 are retained against possible displacement. Rearwardly of the tensioning rollers 19 there is provided a series of tension springs 62, in substantial alignment with the strings 15, and each of the springs 62 is connected at one end to one of the tensioning rollers 19 by a flexible metal

strip 63 which is coiled over the roller in a direction counter to that of its associated string 15, the end of the strip 63 being secured by a pin (not shown) which is adapted to be engaged within a suitable hole in the periphery of the roller. The other end of each tension spring 62 is connected to a wrench faced stud 64 by a wire 65 which is wound thereupon and secured thereto in a suitable manner. The studs 64 are mounted threaded on the body of the instrument and are rotatable by means of a hand key or like instrument for the purpose of adjusting the tension of the springs 62.

In preparing the instrument for practice of the invention, it is required that the instrument be first tuned to basic or normal tensional adjustment of the strings. This may be readily accomplished by manipulation of the conventional tuning keys 14, whereby each string is individually tensioned to its normal pitch. It will be understood that during the aforesaid tuning operation, the operating levers 38 of the auxiliary tuning means are retained in neutral position within the centrally located recesses or notches 50 of the index bars 48. The studs 64 are then rotated with a suitable key wrench or the like, to adjust the tension springs 62 so that each of the springs exerts a tension upon its associated tensioning roller 19 equal to the tension exerted by the string 15 at its normal pitch adjustment. In view of the fact that the strings 15 and the connecting strips 63 of the springs 62 are wound upon the tensioning rollers in opposite directions, and the opposite tensions upon each tensioning roller are equally balanced, as heretofore pointed out, it will be apparent that each tensioning roller is thus normally maintained against rotation in either direction.

It will be evident, that when the tensioning roller 19 is rotated, as upon movement of the operating lever 38 to an adjusted position, the opposite tensions of the string 15 and the spring 62 thereby become unbalanced. For example, when the lever 38 is operated for rotating the tensioning roller 19 so as to increase the tension of the connected string above its normal tensional adjustment, then the tension of the spring 62 will be relaxed below its normal tensional adjustment; likewise, when the lever 38 is moved to rotate the tensioning roller so as to decrease the tension of the connected string below its normal tensional adjustment, then the tension of the spring 62 will be increased above normal tensional adjustment. When, therefore, the lever 38 is released from a retained position of above normal tensional adjustment, and returned to neutral position, then the increased tension of the string 15 will tend to counter rotate the tensioning roller 19 toward its normal tensioning position. In a similar manner, when the lever 38 is released from a retained position of below normal tensional adjustment, and returned to neutral position, then the increased tension of the spring 62 will tend to counter rotate the tensioning roller 19 toward its normal tensioning position. The foregoing balancing arrangement is therefore designed to urge the tensioning rollers 19 at all times toward position for restoring the strings to a state of normal tensional adjustment.

In the practice of the invention, each of the operating levers is adapted for movement by the hand of the player into five distinct adjusted positions, namely neutral position, and two positions on each side of the neutral position. These positions of adjustment are preferably arranged to

provide for adjusting the tension of the strings in equal steps, so that the pitch of each string may be varied a half-tone upon movement of the corresponding lever from one adjusted position 5 to an adjacent position. Each of the strings may thus be stretched two half-tones above normal pitch and contracted two half-tones below normal pitch.

From the foregoing disclosure, it will be clear 10 that the novel tuning or tensioning mechanism constituted by the instrumentalities illustrated and above described, provides for a wide range of pitch variation of each string, and for rapid execution with but little effort on the part of the 15 player and under his control at all times.

That the present invention has achieved the 20 stated object of increasing to an infinitely greater extent, the number of chord combinations which may be obtained by the player of a stringed instrument will be realized when it is considered 25 that in the instrument herein illustrated by way of example it is possible to secure five half-tone pitch variations for each of seven strings, the various pitches of the strings being capable of grouping in many different combinations. One 30 can readily appreciate the almost incalculable number of chord combinations possible in a stringed musical instrument having an indefinitely greater number of pitch variations for each of a much larger number of strings limited only by 35 considerations of space and convenience in structural arrangement, the invention being of universal application and amplification.

While we have illustrated and described herein 40 the now preferred embodiment of our invention, it is however to be clearly understood that we do not desire to be limited to the specific details of construction herein shown and disclosed, for obvious changes in construction are contemplated, which will fall within the spirit and scope 45 of our invention as defined in the appended claims.

Having thus described and illustrated our invention, what we claim as new and desire to 50 secure by Letters Patent is:

1. In a stringed musical instrument having a 55 plurality of strings tensioned thereon, means for selectively varying the pitch of each of said strings, said means comprising a plurality of string tensioning rollers mounted on a common axis and independently rotatable thereon, each of said rollers having one end of one of the strings attached thereto and windable thereon to and from a normal tensioning position, a plurality 60 of manually operable levers pivotally mounted upon a common axis and each independently movable to either side of a normal position about said common axis, and means operatively connecting the levers to the string tensioning rollers whereby 65 rotation of any one of said levers will cause a corresponding rotation of its connected string tensioning rollers in either direction from its normal tensioning position upon corresponding operation of its connected lever to thereby vary the pitch of the string attached to the said tensioning roller.

2. In a stringed musical instrument having a 70 plurality of strings tensioned thereon, means for selectively varying the pitch of each of said strings, said means comprising a plurality of string tensioning rollers mounted on a common axis and independently rotatable thereon, each of said rollers having one end of one of the strings attached thereto and windable thereon to and from a normal tensioning position, a plural- 75

ity of manually operable levers pivotally mounted upon a common axis and each independently movable to either side of a normal position about said common axis, means operatively connecting the levers to the string tensioning rollers whereby 80 rotation of any one of said levers will cause a corresponding rotation of its connected string tensioning roller in either direction from its normal tensioning position upon corresponding operation of its connected lever to thereby vary the 85 pitch of the string attached to the said tensioning roller, and a locking device associated with each lever and engaging a fixed part of the instrument to retain said lever and its connected string tensioning roller in a selected string tensioning position of a plurality of possible adjustive positions.

3. In a stringed musical instrument having a 90 plurality of strings tensioned thereon, means for selectively varying the pitch of each of said strings, said means comprising a plurality of string tensioning rollers mounted on a common axis and independently rotatable thereon, each of said rollers having one end of one of the strings attached thereto and windable thereon to and 95 from a normal tensioning position, a plurality of manually operable levers pivotally mounted upon a common axis and each independently movable to either side of a normal position about said common axis, means operatively connecting the 100 levers to the string tensioning rollers whereby rotation of any one of said levers will cause a corresponding rotation of its connected string tensioning roller in either direction from its normal tensioning position upon corresponding operation of its connected lever to thereby vary the 105 pitch of the string attached to the said tensioning roller, a locking device associated with each lever and engaging a fixed part of the instrument to retain said lever and its connected string tensioning roller in a selected string tensioning position of a plurality of possible adjustive positions, and means engaging said levers for releasing said locking devices and returning said levers and their connected string tensioning rollers to their 110 normal string tensioning positions.

4. In a stringed musical instrument having a 115 plurality of strings tensioned thereon, means for selectively varying the pitch of each of said strings, said means comprising a plurality of string tensioning rollers mounted on a common axis and independently rotatable thereon, each of said rollers having one end of one of the strings attached thereto and windable thereon to and 120 from a normal tensioning position, a plurality of manually operable levers pivotally mounted upon a common axis and each independently movable to either side of a normal position about said common axis, means operatively connecting the levers to the string tensioning rollers whereby 125 rotation of any one of said levers will cause a corresponding rotation of its connected string tensioning roller in either direction from its normal tensioning position upon corresponding operation of its connected lever to thereby vary the pitch 130 of the string attached to the said tensioning roller, a locking device carried by each lever and including resilient means for normally urging said locking device to a locking position, and a fixed index member adjacent each lever and engageable by said locking device, said index member having a series of spaced recesses therein to selectively receive said locking device to retain said lever in any one of several adjustive positions.

5. In a stringed musical instrument having a 135

plurality of strings tensioned thereon, means for selectively varying the pitch of each of said strings, said means comprising a plurality of string tensioning rollers mounted on a common 5 axis and independently rotatable thereon, each of said rollers having one end of one of the strings attached thereto and windable thereon to and from a normal tensioning position, a plurality of manually operable levers pivotally mounted upon 10 a common axis and each independently movable to either side of a normal position about said common axis, means operatively connecting the levers to the string tensioning rollers whereby rotation of any one of said levers will cause a corresponding rotation of its connected string tensioning roller in either direction from its normal tensioning position upon corresponding operation of its connected lever to thereby vary the pitch of the string attached to the said tensioning 15 roller, a resilient prong carried by said lever, a fixed index member adjacent each lever and prong, said index member having a series of spaced recesses therein selectively engageable by said prong whereby the lever may be retained in 20 any one of several adjustive positions, and means engaging said levers for releasing said prongs from engagement with selected recesses and returning said levers and their connected string tensioning rollers to their normal string tensioning 25 positions.

6. In a stringed musical instrument having a plurality of strings tensioned thereon, means for selectively varying the pitch of each of said strings, said means comprising a series of string tensioning rollers mounted on a common axis and independently rotatable thereon, each of said rollers having an end of one of the strings attached thereto and windable thereon to and from a normal tensioning position, a corresponding 30 series of manually operable levers pivotally mounted on a common axis and each movable independently of the others to either side of a normal position about said common axis, means operatively connecting the levers to the string tensioning rollers whereby rotation of a selected lever 35 will cause a corresponding rotation of the roller to which it is operatively connected, a resilient locking device associated with each of said levers and engaging a fixed part of the instrument to retain said lever and its connected string tensioning 40 roller in one of a plurality of possible adjustive positions, and a manually operable lever engageable with all of the first-mentioned levers as a group to simultaneously release said resilient locking devices and to return said levers and their 45 connected string tensioning rollers to their normal string tensioning positions.

7. In a stringed musical instrument having a plurality of strings tensioned thereon, means for selectively varying the pitch of the several strings, said means comprising a series of string tensioning rollers mounted upon a common axis and each having one end of one of the strings attached thereto and windable thereon to and 50 from a normal tensioning position, a corresponding series of manually operable sector-levers pivotally mounted on a common axis and movable independently of each other to either side of a neutral position, means operatively connecting each of said sector-levers to its corresponding tensioning roller to rotate said roller upon rotation of its connected string tensioning roller in either direction from its normal tensioning position upon corresponding operation of its connected 55 lever to thereby vary the pitch of the string attached to the said tensioning roller, and a plurality of tension springs aligned with the plurality of strings on the instrument, each of said springs having a flexible connecting member 60 windable upon one of said string tensioning rollers in a direction counter to that of the string, said tension springs urging the tensioning rollers into their normal tensioning positions when the levers are moved to their normal position.

sible adjustive positions, said sector-levers having aligned, similarly disposed body apertures formed therein, a movable cross-bar transfixing said apertures, which bar, when in one position within the body apertures, permits independent 5 movement of said sector-levers to permit locking thereof by said resilient locking device and, when in another position, engages a wall defining the said body apertures, and a lever connected to said cross-bar and operable manually to simultaneously release said sector-levers from their locked 10 adjusted positions and to return them to their neutral positions.

8. In a stringed musical instrument having a plurality of strings tensioned thereon, means for selectively varying the pitch of the several strings, said means comprising a series of string tensioning rollers mounted on a common axis and each having one end of one of the strings attached thereto and windable thereon to and from a normal tensioning position, a corresponding series 15 of manually operable sector-levers pivotally mounted on a common axis and movable independently of each other away from a neutral position, means operatively connecting each of 20 said sector-levers to its corresponding tensioning roller to rotate said roller upon rotation of its corresponding lever, a resilient locking device associated with each of said levers and engaging a fixed part of the instrument to retain said lever 25 resiliently in one of a plurality of possible adjustive positions, said sector-levers having aligned similarly disposed body apertures formed therein, a movable cross-bar transfixing said apertures, which bar, when in one position within the body 30 apertures, permits independent movement of said sector-levers to permit locking thereof by said locking device and, when in another position, engages a wall defining the said body apertures, a pivotally mounted lever connected to said cross-bar and operable manually to bring said cross-bar into locking relation simultaneously with all of the sector-levers, and spring means normally urging said last-mentioned lever and its associated cross-bar into a position to permit independent adjustment and locking of the sector-levers.

9. In a stringed musical instrument having a plurality of strings tensioned thereon, means for selectively varying the pitch of each of said strings, said means comprising a plurality of string tensioning rollers mounted on a common axis and independently rotatable thereon, each of said rollers having one end of one of the strings attached thereto and windable thereon in a given direction, a plurality of manually operable levers pivotally mounted upon a common axis and each independently movable to either side of a normal position about said common axis, means operatively connecting the levers to the string 50 tensioning rollers whereby rotation of any one of said levers will cause a corresponding rotation of its connected string tensioning roller in either direction from its normal tensioning position upon corresponding operation of its connected lever to thereby vary the pitch of the string attached to the said tensioning roller, and a plurality of tension springs aligned with the plurality of strings on the instrument, each of said springs having a flexible connecting member 55 windable upon one of said string tensioning rollers in a direction counter to that of the string, said tension springs urging the tensioning rollers into their normal tensioning positions when the levers are moved to their normal position.

10. In a stringed musical instrument having a plurality of strings tensioned thereon, means for selectively varying the pitch of each of said strings, said means comprising a plurality of 5 string tensioning rollers mounted on a common axis and independently rotatable thereon, each of said rollers having the tailward end of one of said strings attached thereto and windable thereon in a given direction, a plurality of manually operable levers 10 pivotally mounted upon a common axis and each independently movable to either side of a normal position about said common axis, means operatively connecting the levers to the string tensioning rollers whereby rotation of any one of 15 said levers will cause a corresponding rotation of its connected string tensioning roller in either direction from its normal tensioning position upon corresponding operation of its connected lever to thereby vary the pitch of the string attached to 20 the said tensioning roller, and a plurality of tension springs aligned with the plurality of strings on the instrument, each of said springs having one end thereof connected to a fixed support positioned rearwardly of the plurality of 25 string tensioning rollers and each having at its other end a flexible connecting member windable upon one of the tensioning rollers in a direction counter to that of the string connected to said roller, said tension spring counterbalancing the 30 tension of the string on said string tensioning roller.

11. In a stringed musical instrument having a plurality of strings tensioned thereon, means for varying the pitch of each of the strings, said

means comprising a plurality of string tensioning rollers mounted on a common axis and independently rotatable thereon, each of said rollers having the tailward end of one of said strings attached thereto and windable thereon in and from a normal tensioning position, a plurality of manually operable levers pivotally mounted upon a common axis and each independently movable to either side of a normal position about a common axis, means operatively connecting the levers to the string tensioning rollers whereby rotation of any one of said levers will cause a corresponding rotation of its connected string tensioning roller in either direction from its normal tensioning position upon corresponding operation of its connected lever to thereby vary the pitch of the string attached to the said tensioning roller, a plurality of tension springs aligned with the plurality of strings and positioned rearwardly of the plurality of string tensioning rollers, and a plurality of fixed anchorage posts positioned rearwardly of the string tensioning rollers and springs, each of said springs having one end thereof connected to one of the fixed anchorage posts and having at its other end a flexible connecting member windable upon one of the string tensioning rollers in a direction counter to that of the connected string on said roller, each tension spring urging its connected tensioning roller into normal tensioning position.
